CLAIM

The ornamental design for a golf hole flag, as shown and described.

DESCRIPTION

FIG. 1 is a perspective view showing my new design, and showing a fragmentary portion of carrying pole in dot-dashed lines, the pole being shown for illustrative environmental purposes and forms no part of the claimed invention.

FIG. 2 is rear elevational view thereof.

FIG. 3 is front elevational view thereof.

FIG. 4 is a top plan view thereof.

FIG. 5 is a bottom plan view thereof.

FIG. 6 is a right side view thereof; and,

FIG. 7 is left side view thereof.

The evenly spaced broken lines shown in FIGS. 1-7 of the drawings illustrate a pattern of stitching.
